(57) **CLAIM**

I claim the ornamental design for a steering device, as shown and described.

DESCRIPTION

FIG. 1 is a top perspective view of a steering device, showing a first embodiment of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top perspective view thereof in which a baby stroller in broken lines is provided to illustrate an example environment.

FIG. 9 is a top perspective view of a steering device, showing a second embodiment of my new design;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is a top perspective view thereof in which a baby stroller in broken lines is provided to illustrate an example environment.

The broken lines shown in FIGS. 8-16 form no part of the claimed design.
